UNITED STATES PATENT OFFICE

WILLIAM RUSSELL DEGENHARDT, OF LONDON, AND ALLAN FRED DE FRAINE, OF WEMBLEY, ENGLAND, ASSIGNEES TO THE FRANCOIS CEMENTATION COMPANY LIMITED, OF DONCASTER, ENGLAND, A BRITISH COMPANY

EXCAVATING OR TUNNELING APPARATUS

Application filed January 7, 1929, Serial No. 330,899, and in Great Britain January 9, 1928.

This invention relates to excavating or tunneling apparatus of the kind comprising an abrading tool or cutter which is moved over the surface of the rock or other material 5 to be excavated. In certain forms of such excavating or tunneling apparatus the tool or cutter is moved over the whole face of the material to be excavated to form a tunnel or shaft, but in the present invention the chief 10 object is to form a channel so as to leave a central core or part which is disintegrated by blasting cartridges or other suitable means.

According to the invention the abrading tool or cutter is movably supported upon a 15 guide rail or other member shaped to conform with the configuration of the channel to be produced and means are provided for moving the tool or cutter along the said guide rail as the abrading action progresses. The 20 channel thus produced isolates the central portion or core of the material to be excavated either all the way round or over any desired part so that when the core is disintegrated by blasting cartridges the force of 25 the explosion will not be transmitted to the rock or other material on the opposite side of the channel. This result is particularly advantageous when a tunnel is being formed under a river and when there is not a very 30 great thickness of rock or other material between the river bed and the tunnel, under which circumstances it is desirable to isolate the force of the explosion of the blasting cartridges from at least the upper part between 35 the tunnel and the bed of the river. In this case the channel need not necessarily extend through more than a part of a circle, but there may be circumstances in which it 40 is desirable to make a channel extending through a complete circle. Also although the channel will usually be arcuate or circular it 45 may be of other suitable shape according to the shape of the tunnel to be produced; for example it may be oval or rectangular (with rounded corners) or any part of either of such shapes. A further advantage resulting 50 from the employment of this apparatus is that the portion of the wall of the tunnel produced by it is smooth, thereby facilitating the

usual grouting operation as will hereinafter be described.

The aforesaid guide rail may be attached to ring segments carried by the front surface of a suitable structure which may be the last of the supporting rings for the portion of the tunnel already formed. Bearing upon the outer and inner surfaces of this rail are rollers carried by a frame upon which the body of the tool or cutter is mounted. The said frame may extend well to the rear where it is provided with another roller or other rollers for bearing against one or more of the supporting rings already placed in position in the tunnel. The frame is moved to and fro along the guide rail by any suitable means, such for example as a fixed motor operating upon the said frame through a winch and cables connected to opposite sides of the frame. Alternatively the frame may 70 carry the driving motor which would then operate to move the frame through the intermediary of members engaging with teeth or a friction rail carried by the guide rail or a part supporting it or connected thereto. The 75 tool or cutter may be fed forward in any suitable manner as the work progresses, for example by making the body of the tool or cutter adjustable upon the frame so that the 80 tool or cutter can be progressively advanced.

In order that the said invention may be clearly understood and readily carried into effect, the same will now be described more fully with reference to the accompanying drawings, in which:—

Figure 1 is a sectional side elevation showing a constructional form of apparatus according to the invention in position in a tunnel,

Figure 2 is a section taken approximately on the line 2, 2 of Figure 1 and viewed from the rear,

Figure 3 is a plan of the apparatus of Figure 1 removed from its supports in the 95 tunnel,

Figure 4 is a small-scale face elevation of the tunnel with the apparatus in position,

Figures 5 and 6 are sectional elevations of a detail hereinafter described,

Figure 7 is a plan view of another detail also hereinafter described,

Figures 8 is a side elevation showing another constructional form of apparatus according to the invention in position in the tunnel, and

Figure 9 is a front elevation of Figure 8.

A is the abrading tool or cutter carried by a body A¹ mounted upon a frame B having rollers B¹, B² bearing against the inner and outer surfaces of a guide rail C. As shown the apparatus is intended for the formation of a channel of arcuate shape at the upper portion of a tunnel and in this case the said guide rail C is also of arcuate shape and is attached to ring segments C¹ carried by one or more of the supporting rings C², C³ for the portion of the tunnel already formed.

Referring to Figures 1 to 3 the guide rail C is attached to the front part of the last or foremost supporting ring C² with suitable shock-absorbing material C³ interposed and similar material may be placed between the ring segments and the said supporting ring. The frame B is extended to the rear and carries a roller B² for bearing against the inner peripheries of adjacent supporting rings as shown in Figure 1. Lugs B³, B⁴ on part of the frame are connected to cables B⁴, B⁵ one of which passes directly over a pulley B⁵ (Figure 4) at one side of the part tunnel already formed whilst the other cable passes over this pulley after first passing over other pulleys B⁶, B⁷ at the other side. The said cables are disposed in guide grooves formed in the guide rail (which is of channel shape as shown in Figure 1) and are operated by a winch driven by a fixed motor B⁷ as shown in Figure 4. Means may be provided whereby this motor (or the shaft driven by it) is reversed either automatically or by hand as the frame reaches each end of its travel.

The abrading tool A illustrated in Figures 1 to 3 is of the percussion type operated by liquid wave transmission as is well understood and the reciprocating part for striking the tool proper is contained in the tool body A¹ to which pulsating liquid is conveyed from a generator by a flexible pipe attached to an inlet A² leading to the interior of the tool body. Two alternative inlets are shown in Figure 3 one at each side of the tool body and the one that is not used would be plugged in any suitable manner. In this construction the tool A is fed forward as the formation of the channel progresses, by advancing the tool body A¹ upon the frame B and for this purpose a pillar A³ supporting the tool body is carried by a flanged block A⁴ slidably engaging with the side members of the said frame. The said block is moved by means of a screw A⁵ which engages in a screw-threaded hole in a transverse part of the frame and the head of which is connected to the said block so as to be free to rotate. To take the

rearward thrust of the blows of the tool A in the different positions to which the block A⁴ is adjusted, wedges A⁶, A⁷ are provided between the rear part of the tool body and the front part of the last supporting ring. These wedges have serrated co-operating surfaces as shown in Figure 3; the wedge A⁶ is fixed to the rear part of the tool body and the other wedge A⁷ is moved by means of a screw A⁸ which is carried by lugs on a bracket A⁹ attached to the frame and engages in a screw threaded hole in a lug A¹⁰ on the latter wedge. After the screw A⁵ previously mentioned has been adjusted to move the block forward, and the wedge A⁷ has been moved to take up the gap thereby formed, the said screw A⁵ is moved in the reverse direction to bring the block A⁴ slightly rearwards and thereby press the co-operating surfaces of the wedges into firm contact. If desired suitable shock-absorbing material may be interposed between the rear surface of the wedge A⁷ and the front surface of the adjacent supporting ring. The tool may also be advanced by placing distance pieces of different lengths between the tool head and the operating part carried by the body. Figure 5 shows the tool head A connected to the operating part A^x and Figure 6 shows a distance piece a interposed between the head A and the part A^x and suitably connected thereto, for example by pins passing through holes therein or by a bayonet slot connection. This method involves the removal and replacement of the tool head and to enable this to be effected the pillar A³ may be moved about its axis so as to bring the tool head out of the channel that has already been formed. In this method the wedges A⁶, A⁷ can be dispensed with and replaced by a plain thrust block; or the adjustable wedge method can be used in conjunction with the said distance pieces of different lengths which is the intention in the construction according to Figures 1 to 3. When long distance pieces are in use there is a considerable "over-hang" of the front portion of the tool, and to avoid the disadvantages resulting from this we may provide a yoke member A⁰ (Figure 7) which is detachably connected to the tool body A¹ and the front part of which receives and supports the shank of the tool head.

As the surface left by the tool after it has formed a channel is smooth it is possible to effect the grouting operation by making the ring segments C¹ extend close to the surface of the tunnel already formed as shown in Figure 1 and forcing the plastic cement or concrete into the annular space between the last of the supporting rings and the surface of the tunnel as shown in Figure 1, the portion of the ring segments projecting beyond the periphery of the supporting rings serving to prevent the cement from escaping. As an additional precaution against the escape of the

cement small bags of sand or other suitable material may be placed behind the extending portions of the ring segments.

The tool body may be made adjustable in a radial direction so as to vary, as required, the width of the annular space between the surface of the tunnel and the periphery of the supporting rings. This adjustment may be effected as between the aforesaid frame and the tool body when the variation is intended to be only small, but in circumstances where other channels may be required in the face of the material to be excavated, at different radial distances from the centre of the tunnel, the tool body may be adjustably carried by a radially disposed arm which is supported in a similar manner to that above described in connection with the aforesaid frame B.

In the construction shown by Figures 8 and 8 the tool body A¹ is carried by a platform D and is slidably disposed in a transverse hole in a trunnion D¹ which is rotatably carried by a bracket B⁸ on the frame B. The said platform is connected by a link D² to the bracket B⁸ and carries an arcuate rack D³ with which a pinion D⁴ on the bracket B⁸ co-operates. This pinion can be driven from a hand-wheel D⁵ on the frame B through a worm D⁶ and worm-wheel D⁷, the said hand-wheel being operated by a man in a seat D⁸ pivoted to the frame B as shown in Figure 9. By suitably choosing the position of the trunnion D¹ in relation to the position of the pivotal connection between the link D² and the part B⁸ (which pivotal connection represents the pivot about which the platform D rocks) the tool A can be caused to move forward as the work progresses, in an approximately straight line path parallel to the axis of the tunnel when the hand-wheel D⁵ is operated. The said platform also carries a generator D⁹ of usual construction for generating the pulsating liquid supplied to the interior of the tool body through a pipe d⁹, as well as an electric motor D¹⁰ for driving this generator.

In the construction according to Figures 8 and 9 the cable operation of the frame B as described with reference to Figures 1 to 4 is dispensed with by mounting an operating electric motor E on the frame B, this motor driving, through a worm E¹ and worm wheel E², a longitudinal shaft E³ (mounted in the frame B) provided at its ends with pinions E⁴, E⁴ meshing with rack teeth on arcuate guide rails C, C which are suitably carried by certain of the supporting rings C², C² and which in the construction shown are constituted by the inner flanges of H-section girders. Instead of the pinion and rack drive a frictional drive could be provided in which case the pinions would be replaced by friction rollers and the rack teeth by a friction ring. The frame carries at each end

rollers B¹, B¹ for bearing against the inner and outer surfaces of the guide rails, and at its front end has further rollers B^{1x}, B^{1x} bearing against the front and rear surfaces of the front guide rail.

When the frame is driven positively (i. e. by cables as in Figures 1 to 4 or by rack and pinions as in Figures 8 and 9) a suitable friction clutch is preferably provided so that it will slip in the event of any great resistance being met with such as would be provided by falling rock or other material becoming jammed in front of the frame B or the parts moving therewith, although to avoid this as much as possible the tool body may, if desired, have on each side a curved protecting shield.

Although we have shown and described the tool A as being of the percussive type it may be of the rotary or cutter type suitable for the purpose.

What we claim and desire to secure by Letters Patent of the United States is:—

1. Excavating or tunneling apparatus of the kind set forth, comprising an abrading tool or cutter, a guide rail or other member shaped to conform with the configuration of a channel to be produced by the tool or cutter in the face of the tunnel or shaft, a structure supporting the portion of the tunnel or shaft already formed, means for carrying said guide rails or member on said structure, and means for moving the tool or cutter along the said guide rail as the abrading action progresses.

2. Excavating or tunneling apparatus as in claim 1, wherein a frame upon which the body of the tool or cutter is mounted is provided with rollers bearing upon the outer and inner surfaces of the guide rail.

3. Excavating or tunneling apparatus as in claim 1, wherein the guide rail is attached to ring segments carried by the front surface of a suitable structure within the tunnel.

4. Excavating or tunneling apparatus as in claim 1, wherein the body of the tool or cutter is mounted on a frame which is moved to and fro along the guide rail by a fixed motor operating upon the said frame through a winch and cables connected to opposite sides of the frame.

5. Excavating or tunneling apparatus as in claim 1, wherein the body of the tool or cutter is mounted on a frame which is moved to and fro along the guide rail by means of a driving motor carried by the said frame.

6. Excavating or tunneling apparatus comprising in combination with the elements claimed in claim 1, a frame carrying the body of the tool or cutter, a driving motor carried by said frame, members driven by said motor, and a member with which said members engage in order to move said frame along the guide rail.

7. Excavating or tunneling apparatus as in claim 1, wherein means are provided for feeding the tool or cutter forward as the work progresses.
8. Excavating or tunneling apparatus as in claim 1, wherein the body of the tool or cutter is movably carried by a frame and means are provided for moving the said body forward upon the frame as the work progresses.
9. In excavating or tunneling apparatus, the combination with the elements claimed in claim 1 of an adjustable wedge device between the rear part of the body of the tool or cutter and a supporting structure within the tunnel.
10. Excavating or tunneling apparatus as in claim 1, wherein the body of the tool or cutter is slidably disposed in a transverse hole in a trunnion which is rotatably carried by a frame supported by the guide rail.
11. In excavating or tunneling apparatus, the combination with the elements claimed in claim 1 of a frame supported by the guide rail, a trunnion rotatably carried by said frame, a transverse hole in said trunnion for slidably receiving the body of the tool or cutter, a pivoted platform carrying the body of the tool or cutter, and operating mechanism for the tool or cutter, said mechanism being carried by the pivoted platform.
12. In excavating or tunneling apparatus, the combination with the elements claimed in claim 1 of a frame supported by the guide rail, a trunnion rotatably carried by said frame, a transverse hole in said trunnion for slidably receiving the body of the tool or cutter, a pivoted platform carrying the body of the tool or cutter, said trunnion being so disposed in relation to the pivotal axis of the platform that when the latter is swung about its pivot the tool or cutter will move in approximately a straight path parallel to the axis of the tunnel.
13. In excavating or tunneling apparatus, the combination with the elements claimed in claim 1 of a trunnion provided with a transverse hole in which the body of the tool or cutter is slidably disposed, a frame which carries said trunnion and is supported by the guide rail, and a pivoted seat carried by said frame.

WILLIAM RUSSELL DEGENHARDT.
